ARCHERY BOW ARROW REST ACCESSORY
Fred B. Bear, Grayling, Mich., assignor to Bear Archery
Company, Grayling, Mich., a corporation of Michigan
Filed Feb. 2, 1965, Ser. No. 429,823
5 Claims. (Cl. 124—24)

This invention relates generally to bow accessories and more particularly to an attachment for bows comprising means having an adjustable arrow plate as well as a replaceable arrow rest.

Numerous efforts have been made in the past to provide suitable means for accurately supporting and guiding the shaft of an arrow until such time as it leaves the bow on its way to the target. Suitable means for steadily supporting the weight of the arrow are highly desirable to the archer. Formerly, various devices comprising either flexible elements such as bristles or feathers, or rigid devices such as balls or arcuate elements have been utilized for an arrow rest. In most cases these devices are supplied as a permanent attachment to the bow at the time of purchase or, if offered as an accessory, become a permanent part of the bow once installed. This has been a decided disadvantage since every archer has his own personal desire for a specific type of arrow rest and would hesitate to purchase a bow, which he may otherwise desire, if he finds the arrow rest supplied therewith not to his liking.

The foregoing is also true with respect to the numerous variations of arrow plates available with different bows. An arrow plate is designed to laterally position the shaft of the arrow with respect to the archer's line of sight and quite obviously it would be highly desirable to provide means for laterally adjusting the position of an arrow plate with respect to said line of sight so as to accommodate different types and sizes of arrows to the shooting characteristics of different archers. This feature of adjustability is useful not only as the archer changes from one set of arrows to another, but also provides ready means for selecting the best positioning of the arrow shaft when any one particular archer initially begins to shoot with a matched set of arrows.

The present invention overcomes the primary objection to the prior art devices by providing a bow accessory comprising a cover plate easily removable from the bow and including means therewith for supporting an adjustable arrow plate as well as for removably supporting any one of numerous types of arrow rests according to the desires of the individual archer.

The use of a bow sight is becoming increasingly popular among archers and the subject invention includes means readily adaptable to the inclusion of suitable bow sights of well known design in combination with the subject arrow plate and rests.

Accordingly, one of the primary objects of the present invention is to provide a bow accessory including a removable cover plate having an adjustable arrow plate and a removable arrow rest.

Another object of the present invention is to provide a bow accessory including means for removably supporting a variety of types of arrow rests.

A further object of the present invention is to provide a bow accessory including a mounting plate having an adjustable arrow plate and removable arrow rests supported therein and including adjustable sight means.

With these and other objects in view which will more readily appear as the nature of the invention is better understood, the invention consists in the novel construction, combination and arrangement of parts hereinafter more fully described, illustrated and claimed.

The preferred and practical embodiments of the inven-

2

tion are shown in the accompanying drawing in which:

FIGURE 1 is a partial perspective view of the center section of a bow including the sight bar and arrow plate and rest according to the subject invention;

FIGURE 2 is a partial perspective view of the center section of a bow and illustrates the cover plate and its associated elements in exploded relationship to the bow section;

FIGURE 3 is a vertical sectional view taken along the line 3—3 of FIGURE 1 and includes an arrow shaft shown in alternate positions;

FIGURE 4 is a partial rear elevation of the cover plate taken along the line 4—4 of FIGURE 3 with the arrow rest omitted to more clearly illustrate the recesses in the rear of the cover plate;

FIGURE 5 is a vertical sectional view taken along the line 5—5 of FIGURE 4;

FIGURES 6, 7 and 8 are perspective views of various types of arrow rests which may be used in conjunction with the cover plate of the invention.

Similar reference characters designate corresponding parts through the several figures of the drawings.

Referring now more particularly to the drawings, it will be seen from FIGURES 1 and 2 that the invention is shown as applied to a bow section B having a coplanar mounting surface 1 extending upwardly a substantial distance from the horizontal ledge 2 forming the bottom of an open sight window. The preceding construction will be found to exist more or less in the majority of the bow sections now being marketed and in many instances the horizontal ledge 2 is the sole means providing for an arrow rest while the vertically disposed surface 1 acts as the arrow plate. This arrangement alone provides for only one positioning of the arrow shaft, namely the point of intersection between the vertical surface 1 and the horizontal ledge 2.

The present invention proposes means for removably mounting an adjustable arrow plate and a replaceable arrow rest upon the coplanar mounting surface 1 of the bow section. This mounting means comprises a plate or bar, generally designated 3, which is of substantially rectangular shape and of an overall length or height no greater than the height of the vertical coplanar mounting surface 1.

The bar 3 may be modified to provide a sighting bar 4 as illustrated in FIGURE 1. In this instance a vertical slot 5 is provided in the bar 4 for the reception of any suitable type of adjustable sight assembly 6 therein. The cover plate 7, as shown in FIGURES 2 and 3, comprises an element preferably having the same overall dimensions as the sight bar 4 but without the vertical slot 5 in order to permit interchangeability between the two types of bars 3.

Both of the mounting plates or bars 3 are adapted to be flushly mounted within the coplanar surface 1 of the bow section and to be removably secured thereto by means of any suitable attaching means such as the mounting screws 8. A recess 9 is provided in the face of the mounting surface 1 corresponding in dimension to the mounting plate or bar 3 which recess, as will be seen from FIGURE 2, provides a supporting surface 10 against which the rear face 3a of the mounting plate or bar 3 will abut. When it is desired to use the sight bar 4 in combination with the present invention it is necessary to provide a routed sight groove 11 medially disposed between the mounting surfaces 10 in the recess 9 and extending substantially the vertical height of the sight bar 4 beneath the slot 5 in order to accommodate that portion of the sight assembly 6 projecting from the rear of the sight bar 4. Even when the use of the sight bar 4 is not contemplated it is necessary to provide a groove or additional recess in

at least the lowermost portion of the recess 9 for purposes which will become obvious hereinafter.

The arrangement of the mounting of the arrow plate and arrow rests forming the present invention is identical regardless of which form of mounting plate or bar 3 is used. A transverse or horizontal cutout 12 is formed through the lower portion of the bar 3 immediately adjacent the horizontal ledge 2 of the bow section. As will be most clearly seen from FIGURE 4, the cutout portion 12 includes a pair of oppositely disposed side walls 13 parallel to one another and joined at their ends by semi-circular end walls 14. The rear surface 3a of the plate is formed with a pair of supporting ear recesses 15, the radius of which is greater than the radius of the aforementioned semi-circular end walls 14 although the center point for both of these sets of radii is identical. The depth of the recesses 15 is preferably approximately one-half the thickness of the plate 3.

Disposed immediately above the uppermost side wall 13 of the cutout 12 is a tapped opening 16 adapted to receive the arrow plate 17. Suitable threads are provided on the exterior of the circular arrow plate 17 mating with the tapped portion of the opening 16 whereby it will be seen that rotation of the arrow plate 17 will laterally displace the contact face 18 of the arrow plate as clearly pointed out in FIGURE 3. In order to permit rotation of the arrow plate 17 to provide the aforementioned lateral adjustment, a suitable tool-receiving recess 19 is formed in the center of the contact face 18. The recess 19 may be of any suitable shape such as hexagonal for the reception of an Allen wrench.

The reason will now be apparent for providing the routed groove 11 at least in the area of the lower portion of the recess 9, even when using the cover plate 7. When the arrow plate 17 is rotated to its fully retracted position whereupon the contact face 18 thereof will be flush with the outer surface of the cover plate 7, it will be seen that the inner end of the arrow plate will be projected into the groove 11 between the oppositely disposed supporting surfaces 10 as evidenced by the broken line position of the arrow plate in FIGURE 3.

The provision of the horizontal cutout portion 12 adjacent the lower edge of the mounting plate or bar permits the use of any one of several types of arrow rests such as those shown in FIGURES 6-8. FIGURE 6 illustrates a ramp-type arrow rest generally designated 20 which may be formed of any suitable material such as plastic. Preferably one of the so-called self-lubricating types of plastic should be used such as nylon to reduce to a minimum the coefficient of friction between the arrow shaft and the surface thereof.

A feather arrow rest generally designated 21 is disclosed in FIGURE 7 and comprises a plurality of trimmed feathers disposed at an inclined angle with the free ends thereof pointing towards the direction of travel of the arrow.

FIGURE 8 illustrates a bristle arrow rest generally designated 23 and includes a plurality of individual tufts of bristles 24 mounted at right angles to the face of the mounting plate or bar 3.

The three types of arrow rests disclosed in FIGURES 6-8 are among the most popular forms preferred by archers, however, it will be understood that any suitable material may be utilized in forming various other forms of arrow rests so long as suitable mounting or supporting means therefor are provided in accordance with the present invention, as will be described immediately hereinafter.

The ramp-type arrow rest 20 of FIGURE 6 is shown in connection with the bow section and mounting plate or bar 3 illustrated in FIGURES 1-3. The ramp-type arrow rest includes a top deck 25 of substantially triangular shape and disposed in a plane horizontal with

respect to the mounting plate 3. A common feature in all the various embodiments of the arrow rest is that the supporting base to which the various arrow supporting elements are attached is of a common construction. This construction includes a center mounting section 26 having a length and width equal to the length and width of the horizontal cutout portion 12 formed in the mounting plate or bar 3. In fact for purposes of stability, it is important that the periphery of the center mounting sections 26 be substantially congruent with the periphery of the cutout portion 12, there being only enough clearance between the two to permit ready insertion and removal of the center mounting section into and out of the cutout portion 12 as any one of the various arrow rests are inserted from the rear of the mounting plate or bar 3.

Circular supporting ears 27 are disposed at opposite ends of the center mounting sections 26 and are congruent in shape with the supporting ear recesses 15 formed at opposite ends of the cutout portions 12 in the mounting plates. The thickness of the circular supporting ears 27 is equal to the depth of the recesses 15 and since the rear surface of the supporting ears 27 is coplanar with the rear surface of the mounting section 26 it will be apparent that when the arrow rests are inserted through the cutout portion 12 from the rear face 3a of the cover plate 7 that the coplanar surface on the back of the arrow rest will be flushly disposed with respect to the rear face 3a.

From the foregoing description it will be apparent that means have been provided for permitting ready replacement of any one of the arrow rests supported or mounted within a cover plate 7, it only being necessary to remove the mounting screws 8 retaining the cover plate within the recess 9 formed in the mounting surface 1 of the bow section whereupon the arrow rest may be pushed out through the rear face 3a of the cover plate.

The arrow rests are securely retained in the operative position when the mounting plate or bar 3 is attached to the bow section due to the fact that the ends of the circular supporting ears 27 are backed up or supported by the lower portions of the supporting surfaces 10.

It is to be understood that the invention is not limited to the specific features shown, but that the means of construction herein disclosed comprise the preferred forms of several modes of putting the invention into effect, and the invention is therefore plain in any of its forms or modifications within the legitimate and valid scope of the appended claims.

I claim:

1. An attachment for archery bows provided with a sight window, comprising, a mounting plate removably connected to said bow within the sight window, said plate having a horizontal cut-out portion adjacent the lower edge thereof and a tapped opening therethrough above said cut-out portion, a replaceable arrow rest fitted in said cut-out portion and projecting from the outer face of said plate, a threaded arrow plate fitted through said tapped opening and provided with an exposed outer face disposed above said arrow rest, whereby, said arrow plate may be axially adjusted to vary the position of the outer face thereof relative to said arrow rest.

2. An attachment, according to claim 1, wherein the inner face of said mounting plate is provided with a pair of recesses adjacent the ends of said cut-out portion, and said arrow rest comprises a center mounting section adapted to fit within said cut-out portion, and a pair of arcuate supporting ears at the ends of said center section engageable with said recesses.

3. An attachment, according to claim 2, wherein the depth of said recesses and the thickness of said ears are equal to provide a flush surface on the inner face of said mounting plate when said arrow rest is fitted in said mounting plate.

4. An attachment for archery bows, according to claim 2, wherein said bow is provided with a recess in said

sighting window in order to flushly mount said mounting plate therein, and the inner face of said arrow rest abuts the bottom of said recess to retain itself within said mounting plate.

5. An attachment for archery bows, according to claim 2, wherein the outer face of said arrow plate is provided with an axially disposed recess, whereby, said arrow plate maybe axially displaced by the application of a tool within said recess.
